METHOD AND APPARATUS FOR APPLYING
ADHESIVE TO FIBROUS WEBSPeter Kilham, Plainville, Mass., assignor to
American Reinforced Paper Company, Attle-
boro, Mass., a corporation of Massachusetts

Application June 27, 1947, Serial No. 757,511

13 Claims. (Cl. 117—65)

1

This invention relates to the application of liquids, such as adhesives, to webs of various sorts and its object is to apply such liquids uniformly in limited quantities and thereafter to heat the web, desirably under pressure, employing equipment which is effective yet simple and inexpensive.

Various suggestions have heretofore been made for the manufacture of webs from loose, unspun fibers of sisal, jute, cotton, wool, rayon or the like, without weaving or knitting and using adhesive to unite the fibers into a self-sustaining structure. In such structures the adhesive bonds the fibers together where they contact each other and such contacting may occur in various ways. Thus, the fibers may lay in side by side contact with each other for portions of their lengths, or they may cross each other, and such crossings may occur either by an indiscriminate weaving in and out of one of the fibers among others in a single layer, or it will occur more predominantly where the structure is made up of several superposed layers of fibers with fibers in one layer crossing the fibers in the next adjacent layer.

The use of adhesive to unite fibers thus arranged presents a number of problems. The fibers are loose and easily disarranged; it is difficult to distribute the adhesive uniformly in small quantities to bond the fibers where they contact each other and at the same time avoid loading of the web as a whole with adhesive; and it is difficult effectively to apply heat and pressure to the fibers carrying the adhesive, because of variation in thickness of the web and because of the tendency of the fibers to adhere to any heat and pressure applying instrumentalities which they contact.

By the present invention I have provided a method and apparatus which obviate these difficulties.

In accordance with my invention a web of attenuated and generally parallel fibers is advanced over, but out of contact with, a supply of adhesive in which is immersed a pipe having perforations through which air flows into and upwardly through the adhesive to form, on the adhesive surface, a mass of light frothy bubbles of adhesive which rise upwardly from the surface of the adhesive into contact with the web. The bubbles are so fragile that they burst readily upon contact with the fibers and deposit their adhesive sparingly yet uniformly without disturbing the fiber arrangement. The web of fibers is then heated and dried by being drawn

2

over a heated cylinder while being pressed thereagainst by a number of individual pressure applying elements, such as steel balls, which apply a uniform bonding pressure despite variations in thickness of the web and which also act as to minimize adhesion of the fibers to the cylinder. In a modification of my invention a heated cylinder which the web contacts advances at a peripheral speed slightly in excess of the speed of advance of the web so that the cylinder slips relative to the web as a further precaution against adhesion of the fibers to the cylinder.

I contemplate the adaption of this method and apparatus to a number of uses other than specifically for the application of adhesive to fibers of the sort above referred to, as my invention is useful as well for the application of other liquids, such as dyes, and for the treatment of other materials, such as webs of other fibrous materials, like paper strips or wire or fibers composed by textile drawing machinery, cards, combers, etc.; or woven, knitted or netted fabrics; or solid sheets such as paper, metal, wood, plastic and the like.

In the drawings:

Fig. 1 is a side elevation view, partly diagrammatic of a preferred embodiment of my invention;

Fig. 2 is a plan view thereof;

Fig. 3 is a detail plan view of the adhesive tank;

Fig. 4 is a side elevation view thereof;

Fig. 5 is a vertical section on the line 5—5 of Fig. 4;

Fig. 6 is a perspective view of the lower heating cylinder showing the balls and frame;

Fig. 7 illustrates a single layer, fabric-like material which may be made on my machine, and Fig. 7A shows a multi layer material;

Figs. 8 and 8A, 9 and 9A, and 10 and 10A are diagrams indicating the stripping action of the steel balls; and

Fig. 11 is a vertical section of modification.

An unwoven, self-sustaining, fabric-like material which my method and apparatus are well adapted to manufacture is illustrated in Fig. 7 and consists entirely of strands 2 of long, unspun fibers such as sisal drawn out in generally parallel directions, but also contacting each other as in the side contacting areas, a few of which are indicated at 2a, and also at the crossings 2x where one fiber crosses another. Alternatively, a number of layers may be used, as illustrated in Fig. 7A, one layer of fibers 4 crossing the other layer of fibers 2, in which instance there will of course be many additional crossing contacts.

Both the single and the multi layer embodiments are secured together by adhesive which bonds the strands at these places of contact to form a self-sustaining web useful, for example, as a low cost substitute for burlap or for other fabrics made by conventional weaving processes.

At 6 (Fig. 1) is a package of fibers, such as sisal, from which a web 8 of the fibers is drawn and I may use a creel of such packages from which a number of webs 8 are drawn and arranged side by side to give the desired width of web.

The web is supported on an apron 10 drawn around rolls 12 and 13 to support the web as it advances in the direction of the arrow from rolls 11, 12 toward rolls 14 and 15. Both sets of rolls, 11, 12 and 14, 15 nip the fibers, the bottom rolls of each set being power driven and the upper rolls being geared to the lower rolls and resting by their own weight on the fibers supported by the lower rolls. It is desired to attenuate or draft the web for which purpose rolls 14, 15 are driven at a peripheral speed greater than that of rolls 11, 12, this arrangement being merely suggestive of available equipment adapted to draft the fibers to the desired thinness. The drafted fibers 8a constitute the lengthwise strands 2 (Fig. 7) and are sparsely distributed as indicated.

The web 8a passes from the belt 10 through the nip of rolls 14, 15 and thence at 8b over a tank 16 containing adhesive. The adhesive coated web, indicated at 8c, passes in peripheral engagement with the heated drum 18 and the final product, designated 8d, is wound up at 20.

The tank 16, shaped in cross-section as shown in Figs. 1 and 5, is at least co-extensive with the web widthwise and contains a supply of adhesive 22 admitted from a source through the pipe 24 opening into the tank. To make the product above described the adhesive is desirably of the starch type, set up by heat. The adhesive is maintained at a level indicated at 22a somewhat below the path of travel of the web. At 26 is a pipe extending across the tank (Figs. 3 and 4) leading from a supply of compressed air and having a number of holes 28 through which air streams or bubbles 36 flow upwardly through the adhesive in the tank. A water jacket 30, through which cold water, having ingress at 32 and egress at 34, circulates, is provided to insulate the adhesive 22 from the heat of the drum 18 (Fig. 1).

From the adhesive tank the web, indicated at 8c, passes between cylinders 18 and 19 either or both of which are heated as indicated diagrammatically at 18a and 19a.

Suitably supported immediately above the cylinder 18 and extending toward the nip of cylinders 18 and 19 is a frame 40 constructed of end members 42 and 44 (Fig. 6) arcuately shaped to conform to the curvature of cylinder 18 and defining an enclosure bounded at one side by a third frame member 46 and at the other side by the nip of cylinders 18 and 19. The purpose of the frame is to confine a number of steel balls 50 which have entire freedom of movement within the confines of the frame and which roll about on the web 8c as it issues from between cylinders 18 and 19. The frame does not touch either cylinder and is supported above cylinder 18 for freedom of clearance of web 8c beneath it.

As the web 8, attenuated at 8a approaches the adhesive tank 16 it is fragile in construction, so that the fibers must be handled with care to

7 avoid disarrangement by the application of adhesive or the application of heat and pressure.

8 The bubble mass of adhesive rising from the surface 22a of the liquid in tank 16 is preferably 5 composed of sizeable and fragile bubbles as contrasted, for example, with fine, compact lathers that can be worked up with a soap solution. Desirably the bubbles are in the order of a half an inch or so in diameter. The bubbles are more 10 fragile than the web and hence do not disarrange the fibers but burst readily upon contact therewith to deposit their adhesive thereon. Some of the bubble mass works its way through the gaps 15 in the web to its upper surface (Fig. 5) where they burst and thus the adhesive is deposited uniformly throughout the exposed surfaces of the fibers, but in sparing amounts.

The dimensions and character of the bubbles 20 may of course be varied widely, such as to adapt the treatment to different materials, namely unspun fibers other than sisal, or woven, knitted or netted fabrics, or solid sheets such as paper, wood, metal or plastic, and also depending upon 25 the purpose of the treatment, that is, whether to apply adhesive or a dye or for other uses. Generally speaking the higher the air pressure in pipe 26 the more bubbles will be produced, and the thicker or higher viscosity the liquid 22 the larger the bubbles, and vice versa. For the specific 30 manufacturing operation herein described I employ a starch adhesive containing a wetting agent, such as the sulphonated alcohols available commercially as Aerosol, the adhesive having a viscosity of about that of thin cream, or in 35 the order of about 200 centipoises. In practice I have used effectively air holes 28 (Fig. 3) about $\frac{1}{16}$ inch in diameter and spaced about $\frac{3}{4}$ inch apart with an air pressure of about one pound or less per square inch. If the pipe 26 is too 40 near the surface 22a of the adhesive the air may blow through without forming an adequate bubble mass and I have found that a depth of immersion of one inch is usually not enough but that it should be about 2 inches. These details 45 may, of course, be varied widely as I have suggested, and indeed a gas other than air can be used for certain purposes.

50 As the web 8c, wet with adhesive, passes through the nip of cylinders 18 and 19 its fibers are not disarranged and it passes thence under the balls 50. As indicated in Figs. 1 and 6 the frame curves over the top of the cylinder 18 so that the balls roll by gravity both toward the nip of cylinders 18 and 19 and toward the outer member 46 of the frame. These balls have several functions; they apply pressure to the web as the adhesive sets up under the heat particularly of the lower cylinder 18, so that their weight must be adequate for that purpose and in practice I have used balls of about $\frac{5}{8}$ inch diameter made of steel. The balls are effective to distribute adhesive which, due to its surface tension, tends to coalesce in uneven masses, particularly at the areas of fiber contact, and by distributing 65 the adhesive more evenly the heating time necessary to set up such masses of adhesive is obviated so that the overall heating time is reduced. The balls are also effective to "doctor" the lower cylinder 18 of wet or dried adhesive by contact therewith in the spaces between the fibers and any adhesive thus collected by the balls rubs off, after drying, as the balls rub against each other.

70 The balls, furthermore, by rolling against the upper cylinder 19 not only "doctor" it of adhesive but also strip it of fibers that tend to ad-

here to it and pull away from the body of the web. This fiber stripping action is indicated diagrammatically in Figs. 8 and 8A, 9 and 9A, and 10 and 10A. Figs. 8, 9, and 10 are enlarged diagrammatic side views taken at the nip of cylinders 18 and 19 showing the inner row of balls 50a which, by gravity, rest both against the web and against the surface of the upper cylinder. The next row of balls is designated 50b. Figs. 8A, 9A, and 10A are diagrams in plan showing the rows 50a and 50b of steel balls. In these views the dot-dash line A designates the nip of the cylinders 18 and 19 and the dot-dash line B designates the line of contact between the upper cylinder 19 and the row of balls 50a.

As the web 8c moves out from the nip of cylinders 18 and 19 toward the first row of balls 50a, let us assume that a single fiber strand C partially adheres to the surface of cylinder 19 as indicated in Figs. 8 and 8A. As the web advances, one portion of the strand tends to follow the cylinder 19 and the other tends to follow the web as a whole and as this advance continues the strand becomes wedged between adjacent steel balls in row 50a as indicated at C' in Figs. 9 and 9A. As the adjacent balls in row 50a rotate counter-clockwise, (Fig. 9) they pull the strand away from the cylinder 19 and deliver it to the row of balls 50b under which it rolls as shown at C'' (Figs. 10 and 10A) and the stripping action is complete. Although an adhered fiber may not be disposed in just the way I have illustrated yet the steel balls do have a stripping action performed by grasping portions of the fibers and pulling them away from the cylinder to which they are adhered. The balls themselves keep fairly free of adhesive and the fibers do not tend to wind around the balls because of their small diameter and smoothness.

In the embodiment of my invention illustrated I have found that little or no adhesion of fibers to the bottom cylinder occurs. The web 8d preferably continues its contact with the cylinder 18 for a sufficient distance after leaving the ball frame 40 to assure setting up of the adhesive. Thereafter the finished web is rolled up at 20.

Although I prefer to employ two heating cylinders with a ball frame, as above described, this may not in all instances be necessary as I have employed successfully, particularly with less viscous liquids, a single heating cylinder with or without a ball frame. Thus, I have shown a modification in Fig. 11 in which only one cylinder, designated 18, is employed and in cooperation therewith is a heating shoe 60, heated at 61, between which and the cylinder 18 the web 8c passes. To assure stripping of the web from the cylinder 18 I preferably drive it faster, for example from 1% to 5% faster, than the web, as determined by the peripheral speed of the rolls 14, 15 (Fig. 1) and thus I assure that the web and cylinder slide relative to each other and no adhesion of fibers to the cylinder occurs.

The foregoing is directed to the manufacture of a single layer of material as illustrated in Fig. 7. Where two or more layers are desired, as illustrated in Fig. 7A, I preferably first form, for each layer, a self-sustaining structure as above described and then superpose as many layers as desired, uniting the layers by repeating the treatment with adhesive and heat to bond the superposed layers to each other. Alternatively, I may deposit loose crossing strands on the web 8a of Fig. 1 before it is treated with adhesive and subjected to heat and pressure, but I prefer to make

the composite layer out of layers that have been individually prefabricated.

In the claims, the term "web" includes all of the materials above referred to, except where otherwise indicated.

I claim:

1. Apparatus for applying liquid to a web, including a liquid supply tank, means for conducting gas to the liquid contained in said tank to form a bubble mass, a pair of feed rolls for delivering a web of material over the tank, a cylinder on the opposite side of the tank from the rolls, a heat source adjacent the cylinder for applying heat to the web as it advances over the cylinder, a drive rotating the rolls at a predetermined peripheral speed, and a drive rotating the cylinder at a peripheral speed greater than that of the rolls so that a web held by the nip of the rolls will slip relative to the cylinder.
2. The apparatus as defined in claim 1 in which the cylinder is driven about 5% faster than the rolls.
3. Apparatus for applying liquid to a web, including an open liquid supply tank adapted to contain a liquid capable of bubble formation upon the injection of a gas below the surface thereof, means for conducting gas to, and below the surface of the liquid to form a bubble mass, feeding means for delivering a web of material over the tank but out of contact with the liquid, and a heated cylinder to receive the web after it has left contact with the bubble mass.

4. Apparatus for applying liquid to a web, including an open liquid supply tank adapted to contain a liquid capable of bubble formation upon the injection of a gas below the surface thereof, means for conducting gas to, and below the surface of the liquid to form a bubble mass, feeding means for delivering a web of material over the tank but out of contact with the liquid to receive the bubble mass from within the tank, a heated cylinder to receive the web after it has left contact with the bubble mass, a plurality of balls disposed above and pressing upon the web as the web moves over the surface of the cylinder, and a frame for holding the balls in position.

5. Apparatus for applying liquid to a web, including an open liquid supply tank adapted to contain a liquid capable of bubble formation upon the injection of a gas below the surface thereof, means for conducting gas to, and below the surface of the liquid to form a bubble mass, feeding means for delivering a web of material over the tank but out of contact with the liquid to receive the bubble mass from within the tank, a pair of rotatable cylinders positioned one above the other to receive and nip the web after it has left contact with the bubble mass, a guide directing the web around and in contact with a predetermined area of the surface of the lower cylinder after the web leaves the nip of the upper and lower cylinders, means for heating and driving the lower cylinder, a plurality of balls disposed above a portion at least of said predetermined area of the lower cylinder to press the web thereagainst as it passes out from between the cylinders, and a frame for holding the balls in position with some of the balls in contact and rotating with the upper cylinder to remove fibers of the web which tend to adhere to the upper cylinder.

6. The method of applying a liquid adhesive to a web of fibrous material which comprises supporting the web adjacent and above but out of contact with the exposed surface of a pool of

liquid adhesive, forcing a gas, inert as respects said liquid adhesive, under pressure upwardly from below the surface of said pool to form and collect on said surface a mass of relatively large fragile bubbles, and passing the web through the bubbles to cause them to burst and deposit their liquid adhesive on the web.

7. The method of applying a liquid adhesive to a web of fibrous material which comprises supporting the web adjacent and above but out of contact with the exposed surface of a pool of liquid adhesive, said adhesive containing a wetting agent, forcing a gas, inert as respects said liquid adhesive, under pressure upwardly from below the surface of said pool to form and collect on said surface a mass of relatively large fragile bubbles, and passing the web through the bubbles to cause them to burst and deposit their liquid adhesive on the web.

8. The method of applying a liquid adhesive to a web of fibrous material which comprises supporting the web adjacent and above but out of contact with the exposed surface of a pool of liquid adhesive, said adhesive having a viscosity in the order of about 200 centipoises, forcing a gas, inert as respects said liquid adhesive, under pressure upwardly from below the surface of said pool to form and collect on said surface a mass of relatively large fragile bubbles, and passing the web through the bubbles to cause them to burst and deposit their liquid adhesive on the web.

9. The method of applying a liquid adhesive to a web of fibrous material which comprises supporting the web adjacent and above but out of contact with the exposed surface of a pool of liquid adhesive, said adhesive having a viscosity of about 200 centipoises and a wetting agent, forcing a gas, inert as respects said liquid adhesive, under pressure upwardly from below the surface of said pool to form and collect on said surface a mass of relatively large fragile bubbles, and passing the web through the bubbles to cause them to burst and deposit their liquid adhesive on the web.

10. The method as described in claim 6, which includes the further step of thereafter simul-

taneously applying pressure and heat to the web on which the adhesive is thus deposited.

11. The method as described in claim 6, which includes the further step of thereafter simultaneously heating the web and supporting one surface of the web while applying pressure to a plurality of selected spaced areas of its outer surface.

12. The method as described in claim 6, which includes the further step of subsequently heating the web and simultaneously supporting one surface of the web while applying rolling pressure to a plurality of predetermined selected areas of its other surface while avoiding pressure in the intervening areas thereof.

13. Apparatus for applying adhesive to a web of unwoven fibrous strands including an adhesive supply tank, means for passing the web over but out of contact with the adhesive in the tank, means for conducting gas under pressure to the tank below the surface of the adhesive to form bubbles therein which rise to the said surface and break upon contacting the passing web thereby depositing their liquid adhesive on said web, and apparatus for applying heat and pressure to the web, wet with the adhesive, including a pair of cylinders, one above the other, adapted to receive the web, the axis of the upper cylinder being out of vertical alignment with the axis of the lower cylinder toward the inlet side of the cylinders, and a plurality of balls disposed at the outlet side of the nip of the cylinders and positioned to rest on a portion at least of the web supported by the lower cylinder, so that the balls on the outlet side roll by gravity into surface contact with the upper cylinder to aid in stripping it of adhered fibers.
